US0D1050840S

(12) **United States Design Patent** (10) **Patent No.:** **US D1,050,840 S**
(45) **Date of Patent:** **** Nov. 12, 2024**

(54) **RING PLIER TIP**

(71) Applicant: **Hong Ann Tool Industries Co., Ltd.**,
Taichung (TW)

(72) Inventor: **Cheng-Wei Su**, Taichung (TW)

(73) Assignee: **HONG ANN TOOL INDUSTRIES CO., LTD.**, Taichung (TW)

(**) Term: **15 Years**

(21) Appl. No.: **29/845,911**

(22) Filed: **Jul. 12, 2022**

(51) **LOC (14) Cl.** **08-05**

(52) **U.S. Cl.**

USPC **D8/52**

(58) **Field of Classification Search**

(57) **CLAIM**

The ornamental design for a ring plier tip as shown and described.

DESCRIPTION

FIG. 1 is a perspective view of a ring plier tip showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof showing a using condition with the pliers.

The broken lines depict portions of the ring plier tip in which the design is embodied that are not considered part of the claimed design.

1 Claim, 8 Drawing Sheets
